LOCK

Filed June 30, 1921

Patented Apr. 17, 1923.

UNITED STATES PATENT OFFICE.

MOREIS SHEINMAN, OF NEW YORK, N. Y., ASSIGNOR TO WILSON BOHANNAN, INC., OF BROOKLYN, NEW YORK, A CORPORATION OF NEW YORK.

LOCK.

Application filed June 30, 1921. Serial No. 481,542.

To all whom it may concern:

Be it known that I, MORRIS SHEINMAN, a resident of New York city, Bronx county, State of New York, and a citizen of the 5 United States of America, have invented certain new and useful Improvements in Locks, of which the following is a specification.

This invention relates to improvements 10 in door locks, one of the objects being to provide a jimmy-proof lock, or a lock provided with means arranged to act independently of the bolt of the lock to prevent the door being forced upwardly by an instrument 15 inserted under the door, even though the bolt be broken off or in any way separated from its casing. A further object of my invention is to improve the mechanism for operating the bolt of the lock. To operate 20 the bolt, I employ means which does not require the cooperation of a spring. As springs are liable to break or in various ways become unfit for use, I have designed a bolt 25 operating mechanism which will move the bolt to a locked or unlocked position or vice versa, without the use of a spring.

I will now proceed to describe my invention in detail, the novel features of which 30 I will point out in the appended claims, reference being had to the accompanying drawing, wherein:—

Fig. 1 is a face view of my improved lock, the cover or back plate being removed, and the studs carried by the striker plate being 35 shown in section;

Fig. 2 is a face view of the striker-plate having illustrated in connection therewith a portion of the back or cover plate for the lock;

Fig. 3 is an edge view of the lock looking from the top, the lock being illustrated as attached to a door and having illustrated in connection therewith the striker plate and a pin cylinder lock, the fragmentary portion 45 of the door and door frame being shown in section:

Fig. 4 is a sectional view of the lock, the section being taken on line 4—4 in Fig. 1, the bolt being illustrated in elevation and 50 its latch omitted;

Fig. 5 is a fragmentary sectional view of the lock illustrating the bolt operating devices, other parts being omitted;

Fig. 6 is a fragmentary detail view illus-

trating the key operated cam to operate the 55 bolt; and

Fig. 7 is a sectional diagrammatic detail view illustrating the bolt operating device.

As herein embodied, my invention consists of a casing 8 supporting a bolt 9 which 60 is slidable transversely of the casing 8. The portion 10 of the bolt which projects beyond the casing is provided with openings, each opening consisting of a slot 11 and 65 passages 12, the diameter of the passages exceeding the width of the slots. The openings in the bolt are designed to receive studs 13 carried by a striker plate 14, the striker plate being secured to the frame 15 for the door 16. Each stud 13 consists of a shank 70 17 having a head 18, the diameter of the heads exceeding the width of the shanks. The passages 12 in the bolt portion 10 will be slightly larger than the heads 18 of the 75 studs, so that said heads will pass through the same. The width of slots 11 will be such as to receive the shanks 17 of the studs. When the door is in unlocked condition and closed, the studs 13 will be located within passages 80 12, as indicated in Fig. 1; hence, the door can be opened. To lock the door, the bolt will be operated to cause shanks 17 to enter slots 11, after which the door cannot be opened, as the heads 18 of the studs will not pass through slots 11. The bolt 9 is provided 85 with guideways 19 to receive the adjacent portions 20 of the end wall of the casing 8. By this means the bolt is slidably supported by the casing.

To prevent the door from being forced 90 upwardly, when locked, sufficiently to cause heads 18 of the studs to aline with passages 12, I provide the member 21 of the striker plate 14 with a recess 22 to receive a lug 23 carried (in this instance) by the back or 95 cover-plate 24 for the casing 8. When the door is closed, lug 23 will enter recess 22 and after the door is locked the engagement of the lug and recess will prevent the door 100 from being raised. To operate the bolt 9, I provide (in this instance) two independently operable devices, one a cam 25 operable by a key from the outside of the door through the agency of a pin cylinder lock 26. Said cylinder being connected to cam 25 by 105 a plate 27, and the other an arm 28 operable by a knob 29 carried by casing 8, the casing being located on the inside of the door. To

the arm 28, I pivotally attach, at one end, a jamb-plate 30, said plate being enlarged as at 31, at its inner end. The jamb-plate 30 passes through a channel 32 in the adjacent end of bolt 9. At each side of the channel 32 there is a wall, said walls being indicated by 33, 33^a, which are a part of a wall 34 extending downwardly from the under surface of the bolt 9. In other words, the under rear surface of the bolt is recessed as at 34^a, Fig. 4, to provide the said downwardly extending walls 33 and 34. Projecting upwardly from the rear upper surface of the bolt are two lugs 35 and 36 which are acted upon only by the key-operated cam 25 to move the bolt 9 transversely of the casing. When knob 29 is turned, the bolt will be operated by the combined action of arm 28 and plate 30, as will hereinafter appear. When the bolt is operated by turning knob 29, the lugs 35 and 36 have no part in the operation. To hold the bolt in locked or unlocked condition, I provide a latch 36 pivoted at one end to bolt 9, at 37, and at the other end engaging a keeper 38. The latch at its free end carries a lug 39, the face 40 of which bears against the keeper when the bolt is unlocked. When the bolt is locked, the face 41 of the lug will bear upon face 42 of keeper 38. Before bolt 9 can be operated to lock or unlock the door, latch 36 has to be moved to cause its lug 39 to clear keeper 38. For the purpose of swinging the latch, I provide the same with a depending lug 43 which extends into channel 32 (see Fig. 4) to be engaged by an upwardly extending lug 44 on plate 30 which is actuated when arm 28 is operated. As can be seen, plate 30 is loosely mounted in the channel 32, and will not operate bolt 9 until said plate is forced against the inner edge 44^a of either wall 33 or 33^a and also against the outer edge 45 of either wall 33, 33^a, depending upon which direction bolt 9 is to be moved. Should bolt 9 be in unlocked position, as indicated in Figs. 1 and 7, plate 30 will be positioned against inner edge 44^a of wall 33 and against outer edge 45 of wall 33^a, the lug 44 bearing lightly against lug 43 on latch 36. To move the bolt to locked position, arm 28 will be moved in direction of the arrow 46 (Figs. 1 and 7). When arm 28 is moved in the direction of the arrow 46 plate 30 will be moved longitudinally of the channel 32 in the direction of the arrow 47, Fig. 1, which movement will cause lug 44 to force latch 36 to the right in Fig. 1, thereby moving lug 39 on latch 36 to a position to clear keeper 38. A continued movement of arm 28 will finally cause plate 30 to bear against inner edge 44^a of wall 33^a and against outer wall 45 of wall 33 (see dotted lines 48, Fig. 7). After the plate has taken this latter position, it will become jambed and further movement of arm 28 will move

the bolt to the locked position, indicated by dotted lines Fig. 7. After plate 30 has become jambed or forced against the walls 33, 33^a and during the final movement of arm 28, it will slide outwardly. The outward sliding of the plate will not take place until the bolt is moved to locked position. After the bolt 9 has been moved to locked position, lug 39 on latch 36 will be located above keeper 38. When bolt 9 has been moved to locked position, it will contact with post 49, Fig. 1, the same as it does with post 50 when in unlocked position. After bolt 9 has been moved to contact with post 49 and during the final movement of arm 28, plate 30 will slide outwardly or toward the left in Fig. 1 until the enlarged end or stop 31 contacts with wall 33^a, Fig. 7, after which arm 28 cannot be moved further. When plate 30 commences to slide outwardly, latch 36 will swing toward the left in Fig. 1, causing its lug 39 to engage face 42 of keeper 38, whereupon the bolt cannot be moved to unlocked position. To maintain latch 36 in position against stop 38, I employ a spring 51. When bolt 9 is moved to locked position, the shanks 17 of studs 13 will enter slots 11, thereby preventing the door from being opened, as has been explained. To unlock the bolt, arm 28 will be moved in a direction opposite to the direction indicated by arrow 46, at which time the action of the plate described for the locking operation will take place. When cam 25 is operated by the turning of a paracentric key inserted in the pin cylinder 26, the bolt 29 will be moved to locked or unlocked position, as the case may be, for the reason that cam 25 will first contact with lug 43, on latch 36, and move the latch away from keeper 28 (see Fig. 6). A continued movement of the cam 25 will result in its striking lug 35 or 36, as the case may be, and thereafter moving the bolt during the continued movement of cam 25. The lugs 35 and 36 on bolt 9 cooperate with the key operated cam 25, but not with the arm 28, but lug 43 on latch 36 cooperates with both cam 25 and lug 44 on plate 30. The enlarged end 31 of plate 30 limits the extent of rotary movement of arm 28; hence, arm 28 cannot be completely rotated, which is an advantage as the lock can be quickly unlocked, owing to the fact that a person does not have to waste time in unnecessary turning of the knob 29.

Having described my invention, what I claim and desire to secure by Letters Patent is:—

1. In a lock mechanism, the combination of a striker-plate having a recess, projections carried by said plate, a casing, a bolt carried by the casing engaging said projections, and a lug carried by the casing to engage said recess.
2. In a lock mechanism, the combination

of a striker-plate having a recess, projections carried by said plate, a casing, a bolt carried by the casing engaging said projections, a cover-plate for the casing, and a projection carried by the cover-plate to engage said recess.

3. In a lock mechanism, the combination of a striker plate, projections carried thereby, a casing, a bolt carried by the casing engaging said projections, a cover plate for the casing, and means carried by the cover-plate to engage the striker plate independently of the engagement of the bolt and projections on the cover plate.

15 4. In a lock mechanism, a casing, a bolt slidably mounted within the casing, a key operated cam to operate the bolt, a knob operated arm, and means carried by the arm arranged to be forced against the bolt to operate same when the arm is actuated.

5. In a lock mechanism, a casing, a bolt slidably mounted within the casing, a latch carried by the bolt to hold same in locked or unlocked position, a key operated cam arranged to first release the latch and thereafter to operate the bolt, a knob operated arm independent of the key operated cam, and means actuated by the arm to first release the latch and thereafter to be forced against the bolt to operate the same.

35 6. In a lock mechanism, a casing, a bolt slidably mounted within the casing, a latch carried by the bolt to hold same in locked or unlocked position, a key operated cam arranged to first release the latch and thereafter to operate the bolt, a knob operated arm, means actuated by the arm to first release the latch and thereafter to operate the bolt, a plate pivotally connected at one end to said arm and engaging means carried by the bolt located adjacent said plate, arranged to engage said plate when said arm has been moved to a predetermined extent, and means carried by the plate to release the latch before said bolt and plate become engaged.

45 7. In a lock mechanism, a casing, a bolt slidable within the casing having a channel at its inner end, an arm within the casing, means to impart to the arm a rotary motion, and a plate pivotally connected at one end to said arm, said plate extending into said channel and arranged to engage the sides of the channel when said arm is actuated, whereby the bolt will be operated.

55 8. In a lock mechanism, a casing, a bolt slidable within the casing having a channel at its inner end, an arm within the casing, means to impart to the arm a rotary motion, a plate pivotally connected at one end to said arm, said plate extending into said channel and arranged to engage the sides of the channel when said arm is actuated, whereby the bolt will be operated, and means carried by the plate to limit the rotary movement of the arm.

9. In a lock mechanism, a casing, a bolt slidable within the casing having a channel at its inner end, an arm within the casing, means to impart to the arm rotary motion, a plate pivotally connected at one end to said arm, said plate extending into said channel and arranged to engage the sides of the channel when said arm is actuated, whereby the bolt will be operated, a latch carried by the bolt arranged to lock the bolt in locked or unlocked position, and means carried by the plate to release the latch before the plate and bolt become engaged.

10. In a lock mechanism, a casing, a bolt slidable within the casing having a channel at its inner end, an arm within the casing, means to impart to the arm rotary motion, a plate pivotally connected at one end to said arm, said plate extending into said channel and arranged to engage the sides of the channel when said arm is actuated, whereby the bolt will be operated, a latch carried by the bolt arranged to lock the bolt in locked or unlocked position, a lug carried by the latch extending into said channel, and a lug carried by the plate to contact with the lug on the latch to release the latch before the plate and bolt become engaged.

11. In a lock mechanism, a casing, a bolt slidable within the casing having a channel at its inner end, an arm within the casing, means to impart to the arm rotary motion, a plate pivotally connected at one end to said arm, said plate extending into said channel and arranged to engage the sides of the channel when said arm is actuated, whereby the bolt will be operated, a latch carried by the bolt arranged to lock the bolt in locked or unlocked position, means carried by the plate to release the latch before the plate and bolt become engaged, and a key operated cam arranged to first release the latch and thereafter to operate the bolt independently of said arm.

12. In a lock mechanism, a casing, a bolt slidably mounted within the casing, a movable arm within the casing located adjacent the bolt, and means operated by the arm normally slidably connected with the bolt and arranged to engage the bolt when the arm is actuated to lock or unlock the same.

13. In a lock mechanism, a casing, a bolt slidably mounted within the casing, a movable arm within the casing located adjacent the bolt, means operated by the arm normally loosely associated with the bolt and arranged to engage the bolt when the arm is actuated in a direction to lock or unlock the same, and a key operated device to actuate the bolt independently of the arm.

14. In a lock mechanism, a casing, a bolt slidable within the casing having a recess at its inner end, a plate loosely mounted in said recess, and knob operated means to force the plate against the sides of the recess

when the bolt is to be operated and arranged to move the bolt after said plate has engaged the sides of the recess.

15. In a lock mechanism, a casing, a bolt 5 slidably within the casing having a recess at its inner end, a plate loosely mounted in said recess, knob operated means to force the plate against the sides of the recess when the bolt is to be operated and arranged to 10 move the bolt after said plate has engaged the sides of the recess, a latch carried by the bolt to hold said bolt in locked or unlocked position, and means associated with the plate to release the latch before the said 15 plate engages the sides of the recess.

16. In a lock mechanism, a casing, a bolt movably mounted within the casing, a movable arm within the casing located adjacent the bolt, connecting means actuated by the arm to operate the bolt and arranged to be 20 moved to a predetermined extent without actuating the bolt, but to operatively connect the arm and bolt after the arm has been moved sufficiently to complete the extent of idle movement of the connecting means, a latch carried by the bolt to lock the bolt in 25 locked or unlocked position, and means associated with said connecting means to release the latch during its idle movement.

MORRIS SHEINMAN.
